UNITED STATES PATENT OFFICE

MAX J. KUNERT, OF KANSAS CITY, MISSOURI, ASSIGNOR TO BLACK-SIVALLS & BRYSON MANUFACTURING COMPANY, OF KANSAS CITY, MISSOURI, A CORPORATION OF DELAWARE

MOLDER'S FLASK

Application filed December 15, 1930. Serial No. 502,456.

This invention relates to foundry practice, and more particularly to the construction of a flask to be used in molding.

It is an object of the invention to provide a light rigid metal flask which is easily handled and is not apt to become broken due to rough usage. It is a further object of the invention to provide integral handles or lug members carrying flask aligning means and which handles are readily grasped to separate the flask and to pick the flask members off the molding board.

It is also an object of the invention to provide flask aligning means which may be readily replaced when worn so that flask members may be retained in correct alignment.

In accomplishing these and other objects of the invention, I have provided improved details of structure, the preferred forms of which are illustrated in the accompanying drawings, wherein:

Fig. 1 is a perspective view of the flask in which the cope and drag are separated.

Fig. 2 is a longitudinal vertical section 25 through the center of the flask, particularly illustrating the handle construction.

Fig. 3 is a detail perspective view of one of the handles.

Fig. 4 is a fragmentary sectional view of 30 a modified form of flask wherein both the upper and lower flanges are turned in to provide an additional sand lock.

Referring to the drawings, in which like numerals indicate like parts throughout the 35 several views, the flask comprises a cope which may be generally designated as 5, and a drag which may be generally designated as 6.

The cope is preferably formed of pressed steel and comprises a rectangular wall portion 7 having one or more inwardly extending peripheral ribs 8 forming sand locks to retain the molding sand. As shown in Fig. 2, the mating face of the cope between the cope and the drag is turned inwardly, as at 9, to form an inturned flange 10 and the opposite edge of the wall is turned outwardly, as indicated at 11, to form an outturned flange 12. The flange 10 cooperates with the peripheral indentation 10 in stiffening the walls of the

flask as well as supporting the molding sand within the mold.

The drag 6 is of similar construction to the cope, having an inturned flange 13 complementary to the flange 10, a peripheral inwardly extending rib 14 and an outturned flange 15 at the portion of the drag remote from the cope, and corresponding to the peripheral rib 8 and the outturned flange 12 of the cope. As is the case with the cope, the inturned flange 13 cooperates with the peripheral rib 14 in retaining the sand in the mold and with the outturned flange 15 in promoting a rigid rectangular flask.

Handles or pin lugs which may be generally designated as 16 and 17 are provided for the ends of the cope and drag, respectively, and are preferably formed from a rectangular strip of metal and pressed into the shape as best illustrated in Fig. 3, to provide a flat vertical attaching portion 18, a horizontally extending portion 19 terminating in a vertical end portion 20, and a horizontal portion 21 having its end 22 terminating in alignment with the attaching portion 18. The horizontal portion 21 is preferably offset as at 23 to provide a finger gripping portion 24 by which the flask members may be lifted from the board in the molding operation.

The portion 21 of the handle on the cope 80 adjoining the drag and the portion of the handle on the drag adjoining the cope are welded in place parallel to and adjacent the flange portions 10 and 13, as shown at 25, so that the handles project outwardly from the flask at right angles to the side thereof and the portion 18 of the handles is welded to the walls of the flask members adjacent the flanges 12 and 15.

When the flask members are inverted on 90 the molding board (not shown) the handles have sufficient clearance to permit a man's fingers being inserted beneath them, in order to readily permit picking up both cope and drag.

The horizontal portions 19 and 21 of the handles on the cope are provided with aligning openings 26, and bushings 27 and 28 are pressed therein as shown in Fig. 2 to receive pins 29 and 30 on the drag, to hold the cope 100

in alignment therewith. The opening in the bushing 27 in one side of the cope is preferably of oval shape having its longer diameter extending longitudinally of the flask to 5 compensate for expansion or contraction between the cope and the drag so that they may be readily separated.

The pins 29 and 30 are provided with reduced shank portions 31 to form shoulders 10 32 and the handle members of the drag are provided with aligning openings 33 and 34 to receive the shanks. The ends of the shanks project through the handles and are threaded to receive nuts 35 by which the 15 pins are retained in position.

The pin 30 and the opening in the bushing 28 are preferably larger than the other pin and opening so that it is impossible to close the mold incorrectly.

20 It is thus apparent that when the pins or bushings become worn they may be readily removed by pressing out the old bushings and removing the nuts which retain the pins after which new parts may be readily inserted.

25 In Fig. 4 is illustrated a modified form of flask wherein both the upper and lower flanges 36 and 37 are turned inwardly to cooperate with the rib 8 for retaining the sand, otherwise the flask is identical to the one 30 previously described.

What I claim and desire to secure by Letters Patent is:

35 1. A flask including a cope and a drag, handle members on said cope and said drag having spaced horizontal portions provided with aligning apertures, a pin having a threaded shank portion received in the apertures of one of the handle members, a nut threaded on the shank to retain the pin, and 40 a bushing received in the apertures of the other handle member and having an elongated opening to receive said pin and compensate for expansion and contraction between said cope and drag.

45 2. A flask including a cope and a drag, handle members on said cope and said drag having spaced horizontal portions provided with aligning apertures, a shouldered pin having a threaded shank portion received in the apertures of one of the handle members, a nut threaded on the shank to retain the pin and prevent spreading of the horizontal portions of the handle members, and a bushing pressed in the apertures of the other handle 50 member and having an elongated opening to receive said pin and compensate for expansion and contraction between said cope and drag.

60 3. In a mold flask, a handle formed of pressed metal and comprising spaced horizontal portions connected by a vertical portion, one of said horizontal portions having an offset to provide a finger grip and the other of said horizontal portions having a lateral attaching flange for bracing the

handle against pressure applied to said finger grip.

4. In a flask including a cope and a drag, handle members on the cope and drag, each including a strip bent to provide spaced parallel attaching portions having aligning apertures and having a connecting portion provided with an inset to form a finger grip between said spaced portions, and interengaging means extending through the spaced 70 portions of the respective handles to prevent spreading of said spaced portions and to align the cope with the drag.

5. In a flask including a cope and a drag, handle members on the cope and drag, each including a strip bent to provide spaced parallel attaching portions having aligning apertures and having a connecting portion provided with an inset to form a finger grip between said spaced portions, a shouldered pin extending through the apertures of one of the handle members, means on the pin for retaining the pin in said apertures and to prevent spreading of said spaced portions, and a bushing pressed into the apertures of the other handle member to receive the pin.

6. In a flask including a cope and a drag, handle members on the cope and drag, each including a strip bent to provide spaced parallel attaching portions having aligning apertures and a portion connecting said spaced portions, a shouldered pin extending through the apertures of one of the handle members, means on the pin for retaining the pin in said apertures and prevent spreading of said spaced portions, and a bushing pressed into the apertures of the other handle member to receive the pin.

7. In a flask of the character described, a handle member formed of pressed metal and comprising spaced horizontal portions, a vertical portion connecting the ends of said horizontal portions and having an offset to form a finger grip, and a laterally directed flange at the opposite end of one of said horizontal portions to brace the handle member against pressure applied to said finger grip.

In testimony whereof I affix my signature.

MAX J. KUNERT.
